DESIGN FOR A JEWELRY DISPLAY STAND

Rudolph J. Warner, Buffalo, N. Y.

Application January 14, 1937, Serial No. 67,065

Term of patent 14 years

To all whom it may concern:

Be it known that I, Rudolph J. Warner, a citizen of the United States, residing at Buffalo, in the county of Erie and State of New York, have invented a new, original, and ornamental Design for a Jewelry Display Stand, of which the following is a specification, reference being had to the accompanying drawing forming part thereof; and wherein Fig. 1 is a front elevation of a display stand showing my new design and Fig. 2 is a vertical sectional view, about on line 2—2 of Fig. 1.

The characteristic feature of the present design is the representation of a pile of coins in the bottom of the finger recess or opening in the ring-like body, such recess or opening being closed by a back wall against which the coins pile, as shown.

I claim:

The ornamental design for a jewelry display stand, as shown and described.

RUDOLPH J. WARNER.
